ELECTRIC VALVE-OPERATING GEAR.

Application filed December 8, 1925. Serial No. 74,200.

This invention relates to an apparatus for operating the valves of an internal combustion engine by means of apparatus such as solenoids.

5 An object of the invention is to do away with the usual valve operating cams and gears and thus eliminate the liability of the various operations occurring in internal combustion engine cycles getting out of 10 time.

A further object comprises the provision of a simple and efficient means whereby one or more engines or blocs of cylinders can be controlled by the same electrical control 15 device.

A still further object is to provide a simple and efficient electrical operating gear whereby the necessity for carrying the usual spare parts in accordance with the present 20 practice may be avoided.

A further object is to eliminate the necessity of carrying spares whereby the added weight is avoided, and the expense, of these 25 spare parts.

25 A further object is to provide a simple and efficient apparatus for reversing marine engines, especially internal combustion engines, whereby the application is extremely simple and practically fool-proof.

30 The invention is illustrated in the drawings, of which—

Figure 1 is an elevation of the head of a bloc of cylinders of an internal combustion engine and showing in diagrammatic form 35 the association therewith of the electrically controlled and regulated device for operating the valves of the bloc;

Figure 2 is a plan view of the mechanism for setting the control device for movement 40 ahead and astern;

Figure 3 is a side elevation of the control lever;

Figure 4 is an end elevation thereof;

Figure 5 is a cross-section through the 45 commutator shaft showing the construction and operation of the commutator drums.

Figure 6 is a section taken on the line 6—6 of Figure 5;

Figure 7 is an elevation of one of the 50 drums;

Figure 8 is an end elevation of one of the exhaust controlled commutator drums;

Figure 9 is a section taken through one of the exhaust commutator drums.

55 The form of the invention shown in the

drawings is a preferred form, although it is understood that modifications in the construction and arrangement of the parts and in the character of the materials used may be adopted without departing from the 60 spirit of the invention as set forth in the appended claims.

In its general aspect the invention comprises a cylinder block, the valves of which are operated by solenoids in combination 65 with electrical commutator means driven by the engine for controlling the operation of the valves through the energization of the solenoids.

The invention further comprises a commutator drum with associated brushes and means for moving the brushes to change their relation with respect to the drums in order to reverse the engine.

The invention further comprises a controller 70 in combination with the valve-actuating solenoids, the regulating commutator drums and the reversing device, and electrical circuits associated with said elements whereby the progressive movement of the 75 controller will sequentially set the engine into operation.

The invention further comprises means whereby the engine only can be reversed when the controller is in the stop position. 80

In the preferred form of the invention shown in the drawings the valve actuating gear is associated with an engine bloc 10. Figure 1 shows solenoids for one cylinder and the electrical timing gear for one set of 85 valves for three cylinders. The solenoids shown are 11, 12, 13, 14 and 15 and actuate the stems 16, 17, 18, 19 and 20 connected to suitable valves in the top of the cylinder bloc. Each of these solenoids is connected 90 by wires to a trunk line wire 21 which extends to one side 22 of a power line in which a switch 23 is located for opening and closing a connection between the electric circuit and the power line. The solenoid 11 controls an air master-valve which when opened will admit air under pressure to the air starting system which is of any type well-known in internal combustion engines, particularly of the Diesel type, where the engine is started by air. The solenoid 12 100 operates the air starting valve for one particular cylinder. The solenoid 13 operates the exhaust valve for said cylinder. The solenoid 14 operates the inlet valve and the 105

solenoid 15 operates the power admission valve. These solenoids are mounted in a bracket 24 attached to the top of the cylinder bloc.

5 Above the engine or located at any suitable point is a commutator shaft 25 driven by a belt 26 passing over a pulley 27 on the shaft and connected at the other end to a pulley 28 on the engine shaft 29. Mounted 10 on the commutator shaft are a plurality of commutator drums 30 to 43 inclusive. These drums are associated with a plurality of brushes 44 to 57 inclusive, which bear on the periphery of the drums. These brushes are 15 mounted on a brush shaft 58. The shaft at one end is provided with a yoke bar 59 fixed to a shaft 60 threaded as at 61 and operated by a hand-wheel 62 so that the brush shaft can be moved laterally to move the brushes 20 laterally across the surface of the drums. A magnetic brake such as 63 engages the control shaft 60 to hold it in fixed position. One side of this magnetic brake is connected by the wire 64 to one side of the power line and 25 the other side is connected by a wire 65 to a contact 66 associated with a control bar 67 to be described later. Another contact 68 is associated with contact 66 and connected by a wire 69 to a wire 70 connected to the 30 other side of the power line.

The commutator drum 30 and the commutator drum 40 are metal drums suitably insulated from the shaft 25 and are in constant electrical contact with the brushes bearing 35 thereagainst. The brush 44 is connected by a wire 71 to a wire 72 leading to a contact 73 mounted on the control bar 67. This wire 72 is also connected to one end of the solenoid 11. The brush 54 is connected by 40 a wire 74 to one side of the power line. The drums 30 and 40 are called feeder drums because their brushes are always in electrical contact therewith. The drum 30 is connected by a continuous wire such as 75 to the 45 drums 31, 32 and 33. The drum 40, which is a feeder drum, is connected by a wire 76 directly to the metallic parts of the drums 34 to 43 inclusive. In other words these two feeder drums feed current to all the other 50 drums.

Figures 5 to 9 indicate the construction of the drums. As shown, the drums comprise metallic pulleys 77 insulated from the shaft 25 by sleeves 78 of insulation, and these 55 drums, with the exception of the feeder drums, are covered by a layer of insulation 79. This insulation however, at selected points is broken away and contact strips such as 80 connected to the metallic portions of the drums extend through the insulation 60 flush with the surface thereof to make electrical contact with the brushes. The feeder wires are connected to the metallic portions of the drums by being connected to suitable 65 binding posts such as 80 and 81. In the

type of drum shown in Figure 8 there is a contact strip 82 which extends partly around the periphery in the middle thereof. There are three drums, 34, 35 and 36, provided with this sort of contact strip 82. These 70 three drums are the drums which control the exhaust valves of the cylinders under control.

As shown in Figure 2 the magnetic brake comprises an electro-magnet 83 having an 75 armature 84 which is attracted to the magnet. This armature is normally held away from the magnet by a spring 85. This magnetic brake is of any standard type, the details of which are not shown, but it is so 80 constructed in accordance with the general practice that the handle 62 can only be actuated when the electro-magnet 83 is energized, and as will be hereinafter made plain, this energization can only take place when 85 the control lever is in the stop position. It will also be noted that I provide auxiliary power lines 86 and 87 with the switch 88, so that if the main power fails auxiliary power can be supplied. This power may be 90 automatically thrown if desired, by relays, which are not shown.

In considering Figures 3 and 4 which illustrate the details of the construction of the control bar and lever, there is provided a 95 base 89 on which is mounted a vertical, sector-shaped pedestal 90, the upper surface of which is curved and provided with notches such as 91. A control lever 92 is provided with a latch 93 to engage these notches. 100

This lever is pivoted at 94 and is connected to a lever 95 which in any suitable manner is adapted to control a supply of fuel to the engine. Lever 92 is provided with a U-shaped yoke 96 carrying a stem 97 held 105 downward by a spring 98. The lower end of the stem 97 engages in a notch 99 in the upper edge of a control bar 100. The stem is also provided with a laterally extending pawl 101 and as the control lever is moved 110 forward it carries the control bar 100 with it until the pawl 101 engages a rising cam surface 102 fastened to the side of the pedestal 90, thus lifting the stem 97 and disengaging it from the notch 99 in the controller bar 100 which is immediately snapped back to a normal position by a spring 103. The controller bar carries an insulated wedge piece 104 which is adapted in a normal position of the bar to be inserted between contact springs 105 and 106 connected to wires 69 and 65 as above mentioned, separating these springs and breaking the circuit between these two wires. When the springs 115 are together the wires are energized. These 120 wires are connected to the magnetic brake above mentioned.

In the operation of the device, assuming that the switch 23 is closed, the control lever 130 is moved forward ever so slightly to with-

draw the wedge 104 and permit the engagement of the spring fingers 105 and 106, thus energizing the electro-magnet 83, allowing the handle 62 to be moved to set the brushes, 5 for example, for the ahead movement of the engine. The controller lever is then further advanced until the contact piece 73 on the bar engages with the contact piece 107 mounted on the side of the pedestal 90, this 10 contact piece being connected by a wire 70 to the power line. As this connection is made the cam 102 engages the pawl 101 and this causes the disengagement of the controller bar 100 which springs back to normal 15 position and causes the deenergization of the magnetic brake, so that the handle 62 can be moved. When the contact pieces 73 and 107 are connected the current flows from the plus side of the power line, as shown in 20 Figure 1, through wire 70, through the contact pieces to wire 72, through the solenoid 11 and returning by way of wire 21 to the other side of the power line. This actuates the air master-valve and the air is admitted 25 into the air trunk lines. The wire 72 is also connected by wire 71 to brush 44 bearing on feeder drum 30 and this drum is connected to the three air starting drums 31, 32 and 33, each of which are connected by wires 30 respectively to the different air starting solenoids such as 12. As the engine is started under air pressure the various commutator drums are rotated and the brushes are successively brought into engagement with the 35 contact segments thereon to actuate the various solenoids in the proper order.

In reversing the engine as the brushes are moved from the ahead position to the astern position they contact with the continuous 40 segment 82 which will energize the exhaust solenoids such as 13 to release the pressure within the cylinders while the engine is being reversed.

This device is exceedingly simple and 45 efficient and is substantially entirely automatic.

What I claim is:

1. An electrical valve operating gear which comprises a commutator shaft, a plurality 50 of commutator drums thereon, a plurality of brushes bearing against the drums, a shaft on which said brushes are mounted, means for moving the brushes with respect to the drums, electro-magnetic braking means for controlling the brush-moving means, and manually operated means for controlling the energization of the braking means.

2. An electrical valve operating gear 55 which comprises a control mechanism including a control lever and a control bar, means

for detachably fastening them together whereby as the lever is moved from a normal position the bar will be moved also, and means in the path of the lever to disengage 65 the detachable fastening means, and means for moving the bar back to normal position when thus detached from the lever, said control lever adapted to actuate fuel-admitting means, a plurality of valves, electro-magnetic means for actuating said valves, and circuit connections and apparatus associated with the control bar for controlling the actuation of said electro-magnetic means.

3. An electrical valve operating gear 70 which comprises a control mechanism including a control lever and a control bar, means for detachably fastening them together whereby as the lever is moved from a normal position the bar will be moved also, 75 and means in the path of the lever to disengage the detachable fastening means, and means for moving the bar back to normal position when thus detached from the lever, a reversing mechanism, an electro-magnetic 80 brake connected thereto and circuit means extending between the brake and the control mechanism, said circuit means being energized by the movement of the control bar from its normal position, and de-energized 85 by the movement of the control bar back to its normal position.

4. An electrical valve operating gear which comprises a commutator drum having 90 spaced arcuate contact segments thereon and a central circumferential continuous segment, a brush engageable with the drum, means for moving the brush laterally across the face of the drum, an engine having an 95 exhaust valve, electro-magnetic means for operating said valve, and connection between said electro-magnetic means and the brush whereby the exhaust valve is operated as the brush is moved from one position to the other.

5. An electrical valve operating gear which comprises a control mechanism including a control lever and a control bar, a fuel throttle connected to the lever, electrical circuit-controlling elements associated 100 with the bar, means for permitting the movement of the bar and the lever for a portion of their travel, means for automatically disengaging them at a predetermined point 105 in their travel, means for returning the bar to a normal position, a reversing mechanism, a magnetic brake associated therewith and means under the control of the bar in its normal position to control the condition of 110 the braking means.

JOHN L. MACPHERSON.
ERIC N. SORENSEN.
